UNITED STATES PATENT OFFICE

2,531,223

ICE TYPE WATER COOLER WITH GASKET
INSULATED TOPFrank G. Kovacs, Caldwell, and Frederic Arnault
Seidler, South Orange, N. J.

Application January 22, 1949, Serial No. 72,127

1 Claim. (Cl. 220—15)

1

This invention relates to new and useful improvements in water coolers, and particularly to those water coolers provided with ice chambers. It is customary to construct an ice type water cooler with an exterior metal shell and an interior metal receptacle for the ice. Insulation material is mounted between these parts. A sheet metal top wall is mounted upon the top of the shell and extends over and connects with the top of the receptacle. It is customary to weld and solder the adjacent portions of the metal receptacle and the metal top wall together. This construction is objectionable, particularly on hot and humid days. It will be found that the "cold" from the metal receptacle will be conducted directly to the metal top and then part way down the metal shell. Consequently, "sweating" of the top portion of the exterior metal shell takes place. This invention particularly proposes a simple construction for separating the top wall from the metal receptacle so as to prevent heat conduction between these parts in order to eliminated the objectionable sweating referred to.

The invention particularly proposes the provision of a heat insulation gasket for separating the adjacent portions of the metal receptacle and the top wall. It is proposed to mount the heat insulation gasket in position in a certain way, and to inter-engage the edge portions of the metal receptacle and top wall so as to hold the gasket in position while at the same time said receptacle and top wall are separated by the gasket.

Another object of the invention is the construction of a device as described which is simple and durable and which may be manufactured and sold at a reasonable cost.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:

Fig. 1 is an elevational view of an ice type water cooler constructed in accordance with this invention.

Fig. 2 is a plan view of Fig. 1 but illustrated with the water bottle and the top cover of the cooler removed.

Fig. 3 is a fragmentary enlarged vertical sectional view taken on the line 3—3 of Fig. 2.

Fig. 4 is a fragmentary enlarged detailed view of a portion of Fig. 3.

2

The ice type water cooler to which this invention applies has an exterior metal shell 10, a metal receptacle 11 within said shell 10 forming a chamber 12 for the ice, and a sheet metal top wall 13 mounted upon the top of the shell 10 and extending over the top edge of the receptacle 11. The usual water reservoir 14 is mounted within the receptacle 11 and projects above its top edge and is provided with the usual rubber ring 15 upon which the inverted bottle of water 16 is rested. The water cooler is also provided with a sectional top cover 17 which may be removed to give access to the ice chamber 12 so that the latter may be packed with ice. The cooler is also provided with the usual water drain 18, water discharge faucet 19, and water discharge shelf 20 upon which a glass or cup may be rested beneath the faucet 19.

Insulation material 21 is mounted across the bottom of the receptacle 11. The space between the receptacle 11 and the exterior metal shell 10 is packed with insulation material 22. Further details of the water cooler itself will not be given in this application as they have no bearing on the invention.

The inventive feature embodied herein comprises a heat insulation gasket 25 engaging between the adjacent edge portions of said top wall 13 and said receptacle 11. Said adjacent edge portions are clamped upon said gasket 25 and are opposed to each other in a certain way in order to secure said top wall 13 and receptacle 11 together in a position separated by the gasket 25. More particularly, the top edge portion of the receptacle 11 is formed with an inturned flange 26. The gasket 25 is engaged over the flange 26 and slightly down from said flange. The inner edge portion of the top wall 13 is formed with a crimped section 27 engaging beneath the flange 26 so as to be opposed to the flange 26 for holding the parts together and at the same time clamping the gasket 25 in position while the gasket acts to separate metal contact of the receptacle 11 and the top wall 13.

The operation of the device may be understood from the following:

The ice type water cooler is used in the usual way. The ice chamber 12 is packed with ice. The gasket 25 acts to prevent conduction of heat between the ice cooler receptacle 11 and the top wall 13 and the top portion of the metal shell 10. Consequently, on hot and humid days the top portion of the metal shell 10 will not sweat. In prior constructions the top wall corresponding with the wall 13, and the top portion of the ice

receptacle were welded and soldered together. Consequently, there was good heat conduction between these parts and the top portion of the shell 10 would become excessively cool and "sweat," which is highly objectionable.

While we have illustrated and described the preferred embodiment of our invention, it is to be understood that we do not limit ourselves to the precise construction herein disclosed and the right is reserved to all changes and modifications coming within the scope of the invention as defined in the appended claim.

Having thus described our invention, what we claim as new and desire to secure by United States Letters Patent is:

In an ice type water cooler, an exterior metal shell having a vertical top edge portion, a metal receptacle for ice mounted in said shell and having an inturned top flange positioned below said top edge portion of said shell, a gasket mounted upon the top portion of said receptacle and engaging around said inturned top flange, a sheet metal top wall having an outer edge portion clamped upon said vertical top edge portion of

said shell, and said top wall having an inner edge portion resting on and clamped around said gasket with its edge located beneath said inturned top flange.
